Meyers, Cushman & Kea

UNITED STATES PATENT OFFICE.

JOHN LEE FERGUSON, OF AKRON, OHIO, ASSIGNOR TO STOKES & SMITH COMPANY, OF SUMMERDALE, PENNSYLVANIA, A CORPORATION OF PENNSYLVANIA.

SEALED WRAPPED PACKAGE.

1,249,607.

Specification of Letters Patent. Patented Dec. 11, 1917.

Application filed October 7, 1916. Serial No. 124,240.

To all whom it may concern:

Be it known that I, JOHN LEE FERGUSON, a citizen of the United States, and residing at Akron, in the county of Summit and State 5 of Ohio, have invented certain new and useful Improvements in Sealed Wrapped Packages, of which the following is a specification.

This invention relates to a sealed wrapped 10 package of the class wherein an exterior cover blank or wrapper is adherently attached to all sides of the box containing the goods, in such manner as to completely close and seal the box against the entrance of air, 15 dirt, vermin or any foreign substance which might result in the deterioration of the goods or in damage to the same.

In the present instance it is my purpose 20 to provide a sealed wrapped package where- in the cover or wrapper blank may be adherently and tightly applied to the box or container with a minimum expenditure of time and labor, inasmuch as such wrapper or cover blank is so formed as to enable it to 25 be readily and conveniently applied to the box through the medium of a wrapping or covering machine.

Still a further object of my invention is 30 the provision of a package of this class wherein the wrapper blank is so cut or formed that very little waste of material results during the manufacture of the blank, yet at the same time such blank may be 35 readily coated with paste or other adhesive substance and then conveyed to the wrapping or covering mechanism of a box covering machine by which it is applied to the box, without the wings or laps of the blank curling or rolling, a difficulty and disadvan- 40 tage usually encountered in attempting to convey an ordinary form of winged or lapped wrapper blank to a wrapping or covering mechanism after one side or face of such wrapper blank has been completely 45 coated with the adhesive.

Another object of the invention is to pro- 50 vide a blank having end wings so formed that each wing is of less width, transversely considered, from its longitudinal free edge to its line of junction with the body of the blank than the width of the panel or section of the blank body with which it is connected, with the result that when each end wing is folded over against the end of the

box, it will not extend completely across 55 such box end but will extend part way across the box end so that it will take two opposing end wings to cover each end of the box, these end wings over-lapping it at their meeting portions and thus give to the box 60 the appearance of having the tucked in or over-lapping ends, usually found in the loose wrapped packages.

With the above recited objects and others 65 of a similar nature in view, my invention consists in the construction, combination and arrangement of parts set forth in and falling within the scope of the appended claims.

In the accompanying drawing:

Figure 1 is a perspective view of a wrap- 70 per blank and a box just prior to the appli- cation of the wrapper to the box.

Figs. 2 to 6 inclusive are perspective views 75 showing the package in various stages of application of the wrapper.

Fig. 7 is a perspective view of a com- pletely wrapped package.

Referring now to the accompanying draw- 80 ings in detail, the letter A designates a con- ventional form of box or package which is to be wrapped; the package in the present 85 instance being shown as oblong in shape. The exterior wrapper or cover for the box A is indicated as an entirety by the letter B, and such wrapper is preferably cut from a 90 thin flexible sheet of material, such as paper or the like. This wrapper blank is so cut or 95 scored as to provide four rectangular panels or sections, and for the sake of convenience the section 1 may be considered as constitut- 90 ing the bottom section of the wrapper and is to be applied to the bottom of the box, while the sections 2 and 3 of the wrapper blank may be considered as the side sections of the 95 blank and the section 4 of such blank may be considered as the top section thereof. The bottom section 1 of the blank is pro- 100 vided with a pair of end laps 5, while the top section 4 is provided with a similar pair of the end laps 6. The side section 2 of the blank is provided with a pair of end wings 7 which are of greater width when measured 105 from their free longitudinal edges to their lines of junction with the blank section 2, than the laps 5 and 6, but are of less width of the section 2 of the blank to which these wings are connected. The other side section

3 of the blank is provided with a similar pair of end wings 8, these wings being preferably substantially the same area and dimensions as the wings 7 just described. In 6 addition the side section 3 of the blank, may be provided with a longitudinal marginal strip 9.

10 The blank is intended to be folded along the transversely parallel lines *a* and along the two longitudinal lines *b*, when the wrapper is being applied to the box. In order that such wrapper may completely envelop the box, and in order to cause the wrapper to tightly adhere to the walls of such box, 15 the inner face of the wrapper is completely coated with an adhesive shown at C.

One method of applying the wrapper to the box will be readily understood by reference to Figs. 1 to 6 inclusive of the drawings, 20 wherein various steps illustrative of this operation are shown. The box A is placed upon the wrapper blank with adhesive coated face of the bottom section 1 of the blank in contact with the bottom of the box. The two side sections 2 and 3 of the blank are then folded up against the side walls of the box and pressed to cause them to adhere to such side walls as shown in Fig. 2. The marginal strip 9 of the section 25 3 of the blank may now be folded down against the top of the box as shown in Fig. 3, and then the top section 4 of the blank is folded down against and caused to adhere to the top of the box, so that the package 30 at this stage has the appearance shown in Fig. 4. The end laps 5 and 6 of the bottom and top sections of the blank are now folded downward and inward against the ends of the box as shown in Fig. 5, and then the end 35 40 wings 8 and 7 of the side sections of the blank are folded inward against the ends of the box to complete the package shown in Fig. 7. By referring to said Fig. 7 it will be noted that adjacent end wings overlap 45 at their meeting portions when the package is completed and that these wings 7 and 8 at each end of the box also over-lie the end laps 5 and 6 adhering to the ends of the box. Therefore, when the box is 50 wrapped as just described, the over-lapping wings in conjunction with the end laps of the blank cause the wrapped box to have tucked or folded end walls somewhat similar in appearance, to the walls of boxes of the 55 "loose wrapped" type. One distinct feature of advantage in connection with the use of the wrapper herein shown, and its application to the box as just described, is that not only is there a minimum amount 60 of material wasted in the cutting or production of the wrapper, but the laps and wings are so short and narrow relative to the body of the blank that they will not curl or roll up to any great extent after the paste or 65 adhesive has been applied thereto, and con-

sequently the wrapper may be easily applied to the box through the agency of an ordinary wrapper applying machine.

While I have herein shown and described one particular embodiment of my invention, I wish it to be understood that I do not confine myself to all the precise details of construction herein set forth by way of illustration as modification and variation may be made without departing from the spirit of the invention or exceeding the scope of the appended claims.

What I claim is:

1. As a new article of manufacture, a sealed wrapped package consisting of a box 80 and a one-piece wrapper completely enveloping and adherently attached to the exterior walls of the box, said wrapper comprising, a blank having a plurality of integrally united sections folded about and 85 adherently attached respectively to the bottom, side and top walls of the box, each of said sections of the blank having wings at the opposite ends thereof attached respectively to opposite ends of the box, each of 90 said wings being of less dimensions than the dimensions of the end walls of the box to which they are attached, and two of said wings overlapping and adherently attached to each other. 95

2. As a new article of manufacture, a sealed wrapped package consisting of a box and a one-piece wrapper completely enveloping and adherently attached to the exterior walls of the box, said wrapper comprising a blank having a plurality of integrally united sections folded about and 100 adherently attached respectively to the bottom, side and top walls of the box, each of said sections of the blank having wings at 105 the opposite ends thereof attached respectively to opposite ends of the box, each of said wings being of less dimensions than the dimensions of the end wall of the box to which they are attached, and two of said 110 wings at each end of the box having converging edges overlapping and adherently attached to each other.

3. As a new article of manufacture, a sealed wrapped package consisting of a box 115 and a one-piece wrapper completely enveloping and adherently attached to the exterior walls of the box, said wrapper comprising a blank having a plurality of integrally united sections folded about and 120 adherently attached respectively to the bottom, side and top walls of the box, each of two of said sections of the blank having short end wings adherently attached respectively to opposite ends of the box, and the 125 other blank sections which alternate with the aforesaid sections each having end wings of greater dimensions than the end wings of the other sections, said end wings of greater dimensions being folded over and adher- 130

ently attached to each other and to the ends of the box.

4. As a new article of manufacture, a sealed wrapped package consisting of a box and a one-piece wrapper completely enveloping and adherently attached to the exterior walls of the box, said wrapper comprising a blank having a plurality of similarly shaped and integrally united sections 10 folded about and adherently attached respectively to the bottom, sides and top walls of the box, each of two of said sections of the blank having relatively short wings at the ends thereof adherently attached respectively to the opposite ends of the box, and

the other blank sections which alternate with the aforesaid sections each having wings at the ends thereof of greater dimensions than the said short wings, said wings of greater dimensions each having converging edges, and said wings being folded over and adherently attached to the opposite ends of the box, with portions of the wings at each box end overlapping.

In testimony whereof I affix my signature 25 in the presence of two witnesses.

JOHN LEE FERGUSON.
